DESIGN FOR AN INSECTICIDE DISPENSER

Llewellynn J. Clark, Grand Rapids, Mich., assignor to The Tanglefoot Company, Grand Rapids, Mich., a corporation of Michigan

Application March 13, 1944, Serial No. 112,881

Term of patent 14 years

(Cl. D31—3)

To all whom it may concern:

Be it known that I, Llewellynn J. Clark, a citizen of the United States and a resident of the city of Grand Rapids, in the county of Kent and State of Michigan, have invented a new, original, and ornamental Design for an Insecticide Dispenser, of which the following is a specification, reference being had to the accompanying drawing, forming a part thereof.

On the drawing:
Figure 1 is an end elevational view of an insecticide dispenser showing my new design.

Figure 2 is a side elevational view, and
Figure 3 is a top plan view thereof.

I claim:
The ornamental design for an insecticide dispenser, as shown.

LLEWELLYNN J. CLARK.
